UNITED STATES PATENT OFFICE.

JAMES MARSDEN, OF WIGAN, ENGLAND.

DESIGN FOR A PATTERN-CHART.

SPECIFICATION forming part of Design No. 29,598, dated November 1, 1898.

Application filed September 21, 1898. Serial No. 691,563. Term of patent 14 years.

To all whom it may concern:

Be it known that I, JAMES MARSDEN, a subject of the Queen of Great Britain, residing in Wigan, in the county of Lancaster, England, have invented and produced a new and original Design for a Pattern-Chart, of which the following is a specification, reference being had to the accompanying drawing, forming a part thereof.

The drawing is a plan view of a pattern-chart, showing my new design.

As shown in the drawing, the leading or material feature of my design consists of a pattern-chart having represented thereon the novel arrangement of patterns for boys' sailor suits, as now described.

Along one side of the pattern-sheet is shown the jacket-facings L L L, the under side of trousers B B B, the top side of trousers A, the facings K, fly C, the sleeves E E, the fly

C, top side sleeve J, cuffs, G G G, sleeve E under side sleeve I, top side of trousers A, and pockets H H. At the opposite side of the pattern-sheet is shown the fore part and back of blouse D D D, facings K K K K K, 25 the sleeve E, collars F F F, flies C C, cuff G, facing K, and top side of trousers A.

Having thus described my invention, what I claim as new therein, and desire to secure by Design Letters Patent, is—

The design for a pattern-chart substantially as herein shown and described.

In witness whereof I have hereunto signed my name, this 5th day of September, 1898, in the presence of two subscribing witnesses. 35

JAMES MARSDEN.
